LIQUID FUEL INJECTION PUMP

Fraser Mackie Evans, Acton, London, England,
assignor to C. A. V. Limited, London, EnglandApplication January 26, 1949, Serial No. 72,954
In Great Britain February 4, 1948

4 Claims. (Cl. 103—38)

1

This invention relates to liquid fuel injection pumps for use with internal combustion engines and of the kind having combined therewith the means for regulating the pump output.

It is already known to provide in combination with the regulating means of such pumps, a stop for determining one of the limits of movement of the said means and thereby determining the normal maximum rate of supply of fuel to the engine, this stop having associated with it a device enabling an extra supply of fuel to be provided by the pump when starting the engine from rest. A disadvantage attending some if not all of such devices hitherto used is that they can be secured by the driver in the position in which the extra supply is always available. Such use of the extra supply device is undesirable, and the object of the present invention is to enable it to be prevented in a simple and convenient manner.

The invention comprises an arrangement in which the manually operable part and a part associated with the normal regulating means of the pump are adapted so to interact that at all times only a temporary extra fuel supply can be obtained.

In the accompanying drawings:

Figures 1, 2 and 3 are sectional views illustrating three different embodiments of the invention.

In Figure 1 of the drawings *a* indicates a slideable rack bar which is adapted to be actuated manually or automatically to vary the output of a reciprocating pump *A* by imparting rotational adjusting movement to the pump plunger or plungers (not shown). Such a rack bar and pump are well known and do not require further description.

The rack bar *a* is movable to the left for increasing the output of the pump, and in the opposite direction for reducing the pump output.

In carrying the invention into effect as shown in Figure 1, there is employed for limiting the movement of the rack bar *a* in the direction for increasing the pump output, a stop consisting of an abutment *b* in the form of a collar which is slideable on a fixed post *c*, and is loaded by a spring *d* tending to move it in the upward direction relatively to the post by the post being secured at its lower end to a housing *e* which forms a chamber containing the post and the adjacent end of the rack bar *a*. The said end of the bar *a* is provided with an adjustable contact piece *f* which when in contact with the abutment *b* determines the normal maximum output of the pump. In one side of the abutment *b* is formed a radial hole *g* which when the abutment is in the posi-

tion shown can be entered by the suitably shaped end of the contact piece *f*. Coaxially with the upper end of the post there is carried by the housing *e* a push button *h* which is loaded by a spring *i*, and through the medium of which the abutment *b* can be moved by the driver into the position shown to bring the hole *g* opposite to the contact piece *f*, the abutment being then held in this position by a catch or pawl *j* loaded by a spring *k*. The pawl *j* is mounted in a transverse hole in the post *c*, and is such that one end of it can be pressed into the hole *g* by the associated spring *k*. The end of the spring *k* remote from the pawl *j* is supported by a ball *m* which engages a longitudinal groove in the abutment *b* for preventing rotation of the latter relatively to the post *c*. Further the inner end of the push button has formed on it a shroud *n* or other projection which can overlap the adjacent end of the abutment *b*. The arrangement is such that the push button *h* can operate the abutment *b* only when the contact piece *f* on the pump regulating bar *a* is clear of the abutment. Otherwise the shroud *n* fouls the contact piece *f* and renders the push button inoperative.

When the engine is at rest, the regulating bar *a* normally occupies a position as shown corresponding to the minimum fuel supply. Also the pawl *j* is out of engagement with the hole *g* in the abutment *b*, and the latter is held by its loading spring *d* in a position higher than that shown so that the pawl cannot enter the said hole. Consequently the abutment *b* is then free to be actuated by the push button *h* for moving the abutment to the position in which the hole *g* is opposite the contact piece *f* and can be engaged by the pawl *j*, the gap between the abutment and the contact piece offering no obstruction to the shroud *n* on the push button *h*. The abutment *b* is actuated as above described by the push button *h* prior to the engine being started. The parts now occupy the positions shown. On turning the engine by an electric motor or otherwise for starting, the regulating bar *a* is moved automatically by the pump governor or manually to the position of maximum fuel supply and as the contact piece *f* can then enter the hole *g* in the abutment the bar *a* can move beyond its normal maximum supply position to enable the pump to give the required extra fuel for starting. On so entering the hole *g* the contact piece *f* presses back the pawl *j* and so disengages it from the abutment, the latter being then held by the contact piece *f* against movement on the post *c* under the ac-

tion of the associated spring d , excepting for a small movement required for preventing the engagement of the pawl with the abutment when the contact piece is withdrawn. This small movement is allowed by making the operative end of the contact piece f of rather smaller diameter than the hole g . When the engine has been started and is running under its own power, the regulating bar a moves to the position for diminishing the fuel supply, and so withdraws the contact piece f from the hole g , allowing the abutment b to be moved to its initial position by its spring d . When, during normal running, the bar a is moved to the position for increasing the pump output the maximum output is determined by contact of the contact piece f with the outer surface of the abutment b , and while the bar a is in this position any attempt by the driver to obtain the extra supply, by again pressing the push button, is prevented by the shroud n on the push button encountering the contact piece on the regulating bar and thus preventing actuation of the abutment. If the abutment c is moved by the push button h to enable the pawl j to engage the hole g at any other time while the engine is running and when the contact piece f is clear of the abutment b only a temporary extra supply is obtainable and this is of no consequence, but if the push button is operated and secured in its operative position, the shroud n then occupies such a position that it prevents the regulating bar a from moving into the normal maximum fuel position. In Figure 2 parts similar to, or serving the same purposes as, parts shown in Figure 1, are indicated by the same reference characters suffixed by 1.

In the arrangement illustrated by Figure 2, I attach one end of the regulating bar a^1 by means of a link 2 to one end of an arm 3 which at the other end is pivotally attached to the interior of the housing e^1 . The contact piece f^1 is in this arrangement adjustably fixed in the closed end of the housing. On the side of the arm 3 adjacent to the contact piece f^1 is slidably mounted an abutment b^1 loaded by a spring d^1 , the abutment being movable against the action of the spring by the inner end of the push button h^1 which is loaded by a spring i^1 . In this example the abutment is attached to the arm 3 by screws 5 passing through slots in the abutment. Also the regulating bar a^1 is movable to the right for increasing the pump output. In the abutment is formed a hole g^1 . The abutment b^1 is held (when depressed by the push button h^1) by a catch or pawl j^1 carried by the arm 3 and loaded by a spring k^1 . The end of the abutment on which the push button can act is situated as shown at a convenient distance from the end of the arm 3 connected to the bar a^1 . The action is similar to that above described. When the engine is at rest and the arm 3 attached to the pump regulating bar a^1 is clear of the contact piece f^1 , and the push button can move the abutment into the position in which the hole g^1 in the bar can engage the contact piece, so enabling the pump to give the extra supply required when starting the engine. While the engine is running, the normal maximum supply is determined by contact of the face of the abutment b^1 with the contact piece f^1 . Moreover while the engine is running under its own power and the bar a^1 is at or near the position of maximum supply actuation of the push button is prevented by the adjacent end of the arm 3 , and at most only a temporary extra supply can be obtained

as a consequence of movement of the abutment by the push button while the arm is in or near the position of minimum supply. Furthermore if the push button be secured by the driver in the depressed position the inner end of the push button prevents the arm 3 from moving under the action of the bar a^1 to the normal maximum fuel position.

In Figure 3, which illustrates a modification of the example shown in Figure 2, parts similar to, or serving the same purposes as, parts shown in Figure 2, are indicated by the same reference characters suffixed by 2 instead of 1. I mount on one side of the arm 3^2 a hollow plunger b^2 which serves as the abutment and is supported at one end by a spring d^2 , the plunger being slidable in a cylindrical bore 6 formed at one side of the arm. Also a catch piece or pawl j^2 is arranged within the plunger b^2 and at one end is pivotally connected to the arm, the said end being adapted to support the spring d^2 in a manner which enables the spring to exert a tilting action on the pawl. The outer end of the pawl j^2 can engage a gapped end portion of the plunger b^2 for holding the same when (as shown) it is moved by the push button h^2 to the position in which an extra fuel supply is obtainable. On starting the engine the arm 3^2 is moved into a position in which the pawl j^2 can abut against the contact piece f^2 and thereby be released. Subsequently the action is similar to that above described, the upper end of the arm 3^2 being adapted by engagement with the inner end of the push button h^2 to prevent a sustained extra supply of fuel from being obtained, and the normal maximum supply being determined by the interaction of the outer surface of the plunger b^2 and the contact piece f^2 . The extent of sliding movement of the plunger b^2 in the bore 6 is controlled by a stop 8 on the arm 3^2 engaging a slot 9 in the plunger.

By this invention it becomes impossible for the driver permanently to obtain the extra supply of fuel during normal running of the engine.

The invention is not, however, restricted to the examples described, as details of construction or arrangement can be varied to suit different requirements.

Having thus described my invention what I claim as new and desire to secure by Letters Patent is:

1. In a liquid fuel injection pump having means for regulating its output, the combination of an abutment and a contact piece which are arranged to co-operate with each other for limiting the movement of the regulating means in the direction for increasing the pump output, and one of which is connected to and movable by the regulating means, a manually operable push button for moving the abutment relatively to the contact piece from a normal position in which the abutment and contact piece co-operate with each other for determining the normal maximum output of the pump to a second position in which the pump output can be increased beyond its normal maximum under the action of the regulating means, a spring for returning the abutment to its normal position, and a catch for temporarily retaining the abutment in the second position, the catch being arranged to be released by the contact piece during movement of the regulating means for increasing the pump output beyond its normal maximum, and the push button being arranged to prevent normal movement of the regulating means in the event of the push button being held down.

2. In a liquid fuel injection pump having output regulating means formed in part by a slideable bar, the combination of a contact piece carried by the slideable bar, an abutment slideable transversely to the bar and arranged to co-operate with the contact piece for limiting the movement of the regulating means in the direction for increasing the pump output, a manually operable push button arranged to overlap one end of the abutment and also to move the latter relatively to the contact piece from a normal position in which the abutment and contact piece co-operate with each other for determining the normal maximum output of the pump to a second position in which the pump output can be increased beyond its normal maximum under the action of the regulating means, a spring for returning the abutment to its normal position, and a catch for temporarily retaining the abutment in the second position, the catch being arranged to be released by the contact piece during movement of the regulating means for increasing the pump output beyond its normal maximum, and the push button being arranged so that, when depressed, it obstructs the normal movement of the regulating means.

3. In a liquid fuel injection pump having output regulating means formed in part by a slideable bar, the combination of a stationary contact piece, a pivotally mounted arm connected to the slideable bar, an abutment slideably carried by the arm and arranged to co-operate with the contact piece, for limiting the movement of the regulating means in the direction for increasing the pump output, a manually operable push button for moving the abutment relatively to the

contact piece from a normal position in which the abutment and contact piece co-operate with each other for determining the normal maximum output of the pump to a second position in which the pump output can be increased beyond its normal maximum under the action of the regulating means, a spring carried by the arm for returning the abutment to its normal position, and a catch for temporarily retaining the abutment in the second position, the catch being arranged to be released by the contact piece during movement of the regulating means for increasing the pump output beyond its normal maximum, and the push button being arranged so that, when depressed, it obstructs the normal movement of the regulating means.

4. A liquid fuel injection pump according to claim 3, in which the abutment has the form of a hollow plunger, and in which the catch lies within and extends along the hollow plunger, one end of the catch being pivoted to the arm, and the spring being arranged to bias the catch towards a position in which it can engage the plunger.
